CARRIER HEAD

James Russell Hornsby, Atlanta, Ga., assignor of
one-third to Henry W. McLarty, Atlanta, Ga.

Application August 29, 1942, Serial No. 456,679

4 Claims. (Cl. 243—36)

This invention relates to an improved carrier head for a pneumatic tube carrier.

An object of this invention is to provide an improved carrier head which is simple in construction, easily assembled, and capable of quick production at relatively small cost.

Another object of this invention is to provide an improved carrier head which includes a cylindrical body, a felt bumper and a pair of leather washers between the bumper and the body, the latter providing a sealing means for frictional contact with the pneumatic tube.

A further object of this invention is to provide a carrier head of this kind which includes an improved indicating means circumferentially adjustable about the head for indicating the particular department from which the carrier is sent.

To the foregoing objects and to others which may hereinafter appear, the invention consists of the novel construction, combination and arrangement of parts, as will be more specifically referred to and illustrated in the accompanying drawing, wherein is shown an embodiment of this invention, but it is to be understood that changes, variations and modifications may be resorted to which fall within the scope of the invention, as claimed.

In the drawing:

Figure 1 is a detail side elevation of a carrier head for a pneumatic dispatch case or carrier, constructed according to an embodiment of this invention;

Figure 2 is an end elevation of the head;

Figure 3 is a fragmentary sectional view, taken on the line 3—3 of Figure 2;

Figure 4 is a fragmentary side elevation of the inner body forming part of the head; and

Figure 5 is a fragmentary sectional view taken on the line 5—5 of Figure 1.

Referring to the drawing, the numeral 10 designates generally a cylindrical body which is adapted to be inserted in a dispatch case, one form of which is shown in dotted lines in Figure 1, and indicated by the numeral 11. The body 10 is formed, intermediate the ends thereof, with an annular, outwardly projecting rib 12, which divides the body 10 into an inner telescoping part 13 which is adapted to be inserted within the dispatch member 11, and the body 10 also includes an outer body part 14 which is substantially shorter in length than the inner body part 13.

A cylindrical sleeve or ring 15 is rotatably mounted on the outer body part and is provided

with a knurled outer surface 16 and also with a window opening 17. The outer periphery of the outer body part 14 is provided with indicia 18 which are adapted to be exposed through the window 17 upon rotation of the sleeve 15 to the desired point. The indicia 18 are adapted to indicate the particular department in a store, building or the like from which the dispatch case emanates.

10 The outer body part 14, at a point below the indicia 18, is formed with an elongated recess or detent 19, and a longitudinally bowed spring 20 is adapted to seat in the recess 19 and bear against the inner side of the sleeve 15 so as to frictionally hold the sleeve 15 in a selected position for exposing the selected indicia 18.

The outer end of the outer body part 14 is formed with an inturned flange 21 and a disc-shaped plate 22 is disposed within the outer body part 14 and bears against the inner side of the flange 21. A fibrous head 23 is disposed upwardly of the body 10, and is of a diameter substantially greater than the diameter of the body 10 and is formed of felt or the like for sliding contact with the inner surface of the pneumatic tube as the dispatch case is drawn along the interior of the tube. The head 23, in the center thereof, is formed with an inwardly extending socket 24 within which a plate 25 is seated. The plate 25 is formed with a pair of inwardly pressed bolt head seats 26 and the heads of a pair of bolts 27 are engageable with the seats 26. The bolts 27 are extended through openings 28 formed in the head 23, and through openings 29 formed in the plate 22. An annular nut forming plate 30 is disposed on the inner side of the plate 22 and is formed with a pair of threaded openings 31 through which the bolts 27 are adapted to be threaded.

40 A pair of washers 32 and 33 are interposed between the inner end of the head 23 and the outer end of the body 10. The washer 32 is substantially greater in diameter than the diameter of the fibrous head 23 and constitutes a sealing member for sealing the dispatch case within the pneumatic tube. The projecting portion of the washer or sealing member 32 is adapted to be bent over, as the dispatch case is inserted in the pneumatic tube, so that the inherent resiliency of the material forming the washer 32 will form a seal to prevent loss of suction and to provide for the free sliding movement of the dispatch case within the pneumatic tube. The washer 33 is disposed between the washer 32 and the flange 21 and is of a diameter smaller than

the washer 32 and substantially equal to the outer diameter of the sleeve 15. The washer 33 constitutes a reinforcing washer for the washer 32 so as to prevent collapse of the projecting portion of the washer 32 when the device is inserted in the pneumatic tube. The two washers 32 and 33 are formed with aligned openings 34 and 35 respectively, which are adapted to register with the openings 28 and 29 so that when the bolts 27 are extended through the openings 28 and 29, and threaded into the plate 30, the two washers 32 and 33 will be tightly held between the body 10, and the head 23.

In the use and operation of this device, the head structure hereinbefore described is adapted to be frictionally inserted within the dispatch case 11, and, if desired, may be secured by means of a bayonet slot and pin, or by friction. The sleeve 15 is rotated about the outer body part 14 to expose the desired indicia 18, which designates the particular department from which the dispatch case emanates. The dispatch case, with the improved head, is then inserted in the pneumatic tube, the head 23 being first inserted so that the washer 32 will be bent inwardly in the direction of the body 10. The suction within the pneumatic tube will then pull the dispatch case to the desired point. The spring 29 will frictionally hold the sleeve 15 about the outer body part 14 so that the sleeve will not be rotated during the movement of the dispatch case within the tube.

The dispatch case 11 is here shown as a cylindrical body with which the head 10 telescopes, but it will be understood that the head 10 may be used with other forms of dispatch cases.

I claim:

1. A carrier head comprising a cylindrical body, an annular bead formed on said body intermediate the ends thereof dividing said body into a long body part for telescopic insertion into a carrier member, and a short outer part, said bead limiting the insertion of said long body part into the carrier member, said outer part having indicia on the periphery thereof, a sleeve rotatable on said outer part and formed with a window for exposing selected indicia, an inturned flange formed on the outer end of said outer part, a cushion head, a pair of flexible washers interposed between said head and said flange, a plate engaging against the inner side of said flange, and securing means engaging through said head, washers and said plate.

2. A carrier head comprising a cylindrical body, 55

an annular bead formed on said body intermediate the ends thereof dividing said body into a long body part for telescopic insertion into a carrier member, and a short outer part, said bead limiting the insertion of said long body part into the carrier member, said outer part having indicia on the periphery thereof, a sleeve rotatable on said outer part and formed with a window for exposing selected indicia, an inturned flange formed on the outer end of said outer part, a cushion head, a pair of flexible washers interposed between said head and said flange, one of said washers having an outer diameter greater than the outer diameter of said head.

3. A carrier head comprising a cylindrical body, an annular bead formed on said body intermediate the ends thereof dividing said body into a long body part for telescopic insertion into a carrier member, and a short outer part, said bead limiting the insertion of said long body part into the carrier member, said outer part having indicia on the periphery thereof, a sleeve rotatable on said outer part and formed with a window for exposing selected indicia, spring means for frictionally holding said sleeve against rotation, an inturned flange formed on the outer end of said outer part, a cushion head, a pair of flexible washers interposed between said head and said flange, one of said washers having an outer diameter greater than the outer diameter of said head, a plate engaging against the inner side of said flange and securing means engaging through said head, washers and said plate.

4. A carrier head comprising a cylindrical body, an annular bead formed on said body intermediate the ends thereof dividing said body into a long body part for telescopic insertion into a carrier member, and a short outer part, said bead limiting the insertion of said long body part into the carrier member, said outer part having indicia on the periphery thereof, a sleeve rotatable on said outer part and formed with a window for exposing selected indicia, said outer part having an elongated recess therein, a longitudinally bowed spring seated in said recess and frictionally bearing against the inner side of said sleeve to frictionally hold said sleeve against rotation, an inturned flange formed on the outer end of said outer part, a cushion head, a pair of flexible washers interposed between said head and said flange, one of said washers having an outer diameter greater than the outer diameter of said head.

JAMES RUSSELL HORNSBY.
